UNITED STATES PATENT OFFICE.

GERTRUDE FLASKAMP, OF HOBOKEN, NEW JERSEY, ASSIGNOR, BY MESNE ASSIGNMENTS, TO ADOLPH HOLLANDER, OF NEW YORK, N. Y.

REINFORCED NECKTIE-SHIELD.

SPECIFICATION forming part of Letters Patent No. 732,537, dated June 30, 1903.

Application filed March 27, 1903. Serial No. 149,822. (No model.)

To all whom it may concern:

Be it known that I, GERTRUDE FLASKAMP, a subject of the German Emperor, and a resident of Hoboken, in the county of Hudson and State of New Jersey, have invented a new and Improved Reinforced Necktie-Shield, of which the following is a full, clear, and exact description.

The invention relates to neckties supported from the front collar-button of a shirt, and its object is to provide a new and improved reinforced necktie-shield arranged to readily connect the clasp with the reinforcing-strip and secure the latter to the shield to strongly reinforce the latter and to securely hold all the parts in proper position.

The invention consists of novel features and parts and combinations of the same, as will be more fully described hereinafter and then pointed out in the claim.

A practical embodiment of the invention is represented in the accompanying drawings, forming a part of this specification, in which similar characters of reference indicate corresponding parts in all the views.

Figure 1 is a rear face view of the improvement, showing the bow attached to the shield. Fig. 2 is an enlarged sectional plan view of the improvement on the line 2-2 of Fig. 1, the bow being omitted; and Fig. 3 is a rear sectional elevation of the button-clasp and the reinforcing-strip, the section being on the line 3-3 of Fig. 2.

The shield A, of pasteboard or other material, covered with a suitable fabric, supports a bow B in the usual manner, and on the said shield A, preferably at the rear face thereof, is secured a reinforcing-strip C, made of sheet metal or the like and provided with integral struck-up prongs C', forced into the material in a curved direction, as plainly indicated in Fig. 2, to securely fasten the reinforcing-strip C to the shield A. The prongs C' are arranged in clusters, which are well distributed over the ends of the strip to insure not only a firm adhesion of the strip on the shield, but also to snugly fit the strip to the face of the shield to conform to the curvature of the shield, as plainly indicated in Fig. 2.

A button-clasp D for engaging a collar-button on the front of the neckband of a

shirt is attached to the shield C to project from the rear face thereof in a rearward direction, and this button-clasp is preferably made from a single piece of spring-wire bent to form jaws D' D', open at the bottom and terminating at their upper ends in doubled-up portions D², extending through an aperture C² in the shield, to the inner or front face thereof, and the lower ends of the jaws D' terminate in transversely-disposed U-shaped members D³, the rear ends of which pass through apertures C³ in the strip C to terminate in the end members D⁴, lying on the front face of the strip between the latter and the shield A and spaced from the doubled-up portions D², so that the button-clasp is securely held in position on the reinforcing-strip.

It is understood that by the arrangement described the jaws D' are held spaced from the rear face of the strip C to leave room for the head of the button, and the jaws D' are yieldingly mounted to allow ready attachment of the button-clasp to the collar-button.

From the foregoing description it will be seen that the reinforcing-strip C is securely fastened to the shield to conform to the curvature thereof and to stiffen the shield, and a firm support is produced for the button-clasp.

Having thus described my invention, I claim as new and desire to secure by Letters Patent—

A reinforced necktie-shield, comprising a shield for supporting the bow of a necktie, a reinforcing-strip having a plurality of integral prongs, distributed over the ends of said reinforcing-strip and curved outwardly into the body of said shield, a button-clasp formed from a piece of spring-wire, the central portion of said wire being bent into an extended loop having parallel sides in close proximity to each other, said clasp being secured at its center and ends to said strip, said extended loop passing through a perforation at the upper side of the strip and extending downwardly against the rear side thereof to a point near the lower edge of said strip, said clasp being provided with button-clamping jaws extending downwardly from the aforesaid perforation at the upper side of the strip, then

upwardly and downwardly again to pass through perforations near the bottom of the strip with their terminals extending upwardly in engagement with the rear side of said strip to near the top thereof, whereby the strip is securely clamped and held between the parts of the button-clasp.

In testimony whereof I have signed my name to this specification in the presence of two subscribing witnesses.

GERTRUDE FLASKAMP.
